DUPLICATING MACHINE

John J. Flanigan, Oak Park, Ill., assignor to Vivid,
Incorporated, Chicago, Ill., a corporation of
Illinois

Application February 3, 1932, Serial No. 590,619

19 Claims. (Cl. 101—133)

This invention relates to duplicating machines of the kind operating on the hectograph principle.

Hectograph duplicating machines commonly employ a band of a gelatinous substance which is wound onto a spindle that is mounted at one end of the machine. The band is stretched across the bed of the machine to provide an impression surface and after successive portions of the band have been used to provide impression surfaces, the band is wound on a take-up spindle at the other end of the machine. The practice heretofore has been to mount the supply roll spindle at the rear of the machine and to provide the take-up spindle at the front of the machine. Prior to use the gelatin band is moistened and this has been done by providing a sponge which is used manually to apply moisture to the band as it is unwound from the supply roll spindle and wound onto the take-up roll spindle. After the band has been moistened and wound upon the take-up roll spindle, the spindles are removed from the machine and interchanged. Automatic moistening devices have been provided which operate on the band to moisten it as it is unwound from the supply roll spindle and wound onto the take-up roll spindle. At the end of this moistening operation, the band is wound on the take-up roll spindle and it is necessary that it be rewound on the supply roll spindle and after this has been done successive portions of the band are withdrawn from the take-up roll spindle and positioned over the bed to provide impression surfaces after which the band is wound onto the take-up roll spindle. When the band is moistened manually or by an automatic moistening device in the above described arrangement, it is necessary to either interchange the spindles or to rewind the band because the supply roll spindle is mounted at the rear of the machine and the take-up roll spindle is mounted at the front of the machine. It is therefore the salient object of my invention to provide a novel hectograph duplicating machine wherein the band is moistened prior to use without interchanging the spindles or rewinding the band.

Other objects are to provide spindle receiving devices at the front of a hectograph duplicating machine so that a gelatin band roll may be expeditiously mounted in the machine and to provide a take-up spindle at the rear of the machine onto which the band may be wound during the moistening operation and from which

the band may be withdrawn to provide an impression surface as it is rewound onto the spindle at the front of the machine; to provide in the machine a novel moistening device in association with a take-up spindle and which will effect moistening of the band as it is unwound from a spindle at the front of the machine and wound on a spindle at the rear of the machine; to provide a rod which will uniformly guide the carriage during repetitious reciprocations thereof over the bed with minimum friction; and to provide a novel winding mechanism operable by a device spaced from the take-up spindle to wind the band in either direction over the bed.

Selected embodiments of the invention are illustrated in the accompanying drawings and therein:

Fig. 1 is a plan view of the machine;

Fig. 2 is a front elevation;

Fig. 3 is a detail view taken substantially on the line 3—3 on Fig. 2;

Fig. 4 is a sectional detail view taken substantially on the line 4—4 on Fig. 3;

Fig. 5 is a fragmentary detail elevational view 25 of the portion of the machine illustrated in Figs. 3 and 4;

Fig. 6 is an elevation of the right hand side of the machine as viewed in Fig. 1, and in which certain parts are broken away;

Fig. 7 is a sectional detail view taken substantially on the line 7—7 on Fig. 6;

Fig. 8 is a sectional detail view taken substantially on the line 8—8 on Fig. 6;

Fig. 9 is an elevation of the left hand side 35 of the machine as viewed in Fig. 1;

Figs. 10 and 11 are elevational detail views of modified forms of the guide bar;

Figs. 12 and 13 are perspective detail views 40 of still other modified forms of the guide bar;

Fig. 14 is a sectional detail view taken substantially on the line 14—14 on Fig. 9 and showing the winding mechanism;

Fig. 15 is a detail view taken substantially on the line 15—15 on Fig. 14 and showing the brake 45 arrangement used in the machine;

Fig. 16 is a detail view taken substantially on the line 16—16 on Fig. 14; and

Fig. 17 is a detail view taken substantially on the line 17—17 on Fig. 14.

In the drawings, 18 is the bed of a duplicating machine which is mounted between the side frame members 19 and 20. At the upper ends of the side members 19 and 20 are trackways 21 and 22 and the carriage C includes rollers 23 55

and 24 which are adapted to travel along said trackways when the platen roller R of the carriage is in upper or non-printing position. However, when the platen roller is moved into its lower or printing position, the carriage travels thereon as the platen roller moves over the portion of the gelatin band B stretched over the bed 18. A duplicating machine embodying a carriage adapted to operate in this manner is described and claimed in my co-pending application, Serial No. 565,283, filed September 26, 1931. In order to insure uniform reciprocation of the carriage over the gelatin band B, a guide rod 25 is provided and the carriage includes a depending portion 26 having bearings 27 and 28 which travel on the guide rod 25 and to insure uniform reciprocation of the carriage. Opposite ends of the guide rod 25 are mounted in the outwardly extending end portions of the cradle 29, Figs. 6 and 8, and the outwardly extending end portions of the cradle are pivotally mounted as at 30 on outwardly extending foot portions on the side frame member 19 so that the guide rod is supported for movement in a vertical plane. Fast to the cradle 29 substantially midway between the ends thereof is a pin 31 which extends through an opening in the side frame member 19 and one end of a spring 32 is fast to this pin, the opposite end of the spring being fast to the spring anchor 33 on the side frame member. This arrangement of the cradle supports the guide rod 25 and the spring 32 acts to urge the guide rod upwardly. However, when it is desired to move the carriage C from position over the band B, it is pivoted on the bearings 27 and 28 about the rod 25, and when this is done the pin 31 engages the upper edge of the slot in the frame 19 through which it is extended to limit downward movement of the rod 25. Such support for the guide rod is described in my referred to co-pending application. To limit reciprocation of the carriage C, a rubber bumper 34 is provided on the guide rod 25 adjacent the front end thereof and this rubber bumper is engaged by the bearing 28 to limit movement of the carriage C and to position it at the front end of the bed. To limit rearward movement of the carriage C, I provide an adjustable stop which consists of a body 35 having a bore 36 therein in which there is a split collar 37 held against rotative movement by the set screw 38. The collar 37 embraces the guide rod 25 and a hand screw 39 is mounted in the body 35 and bears against the split collar 37 adjacent the split therein and by running the hand screw 39 inwardly, the end of said screw engages the collar and forces the ends adjacent the split in said collar toward each other to thereby tightly clamp the body 35 in desired positions along the rod 25. To prevent turning of the body 35 on the guide rod 25 when the screw 39 is loosened, an angle strip 40 is mounted on the cradle 29 and one limb thereof extends into a slot 41 in the side of the body 35. To effectively absorb the shock incident to the engagement of the bearing 27 of the carriage with the stop provided by the body 35, I provide a rubber collar 42 on the rod 25 protected by a flat metal disc 43. As the carriage moves rearwardly the bearing 27 engages the disc 43 and the shock is absorbed by the collar 42 and as the body 35 is at this time tightly clamped on the guide rod, this arrangement will stop the carriage in an identical position upon repetitious reciprocations. The gelatin band B is wound into a roll 44 on a

spindle 53 of the kind, for example, disclosed in the reissued patent to Edward E. McNally, Reissue No. 18,448, May 3, 1932. A spindle of this kind has a journal pin 45 at the end thereof and this pin is adapted to be mounted in the horizontal slot 46 in the frame member 19. At the inner end of the slot 46 is a vertically extending slot 47. A plate 50' is fast on the inside of the side frame member 19 and has a round socket 51' in the forward edge thereof. When the journal pin 45 is in the horizontal slot 46 the periphery of spindle 53 rests in pocket 51' and retains the pin 45 in said slot. Pivotally mounted at 48 on the side frame member 19 is a plate 49 having a pocket 50 therein. The plate 49 is adapted to be pivoted into the position illustrated in Figs. 3 and 6 whereat the pocket 50 embraces the end of the journal 45 to thereby prevent displacement of the journal pin from the horizontal slot 46. A pin 51 on the plate 48 projects through an opening 52 in the side frame 19 and serves to limit the pivoting movement of the plate 49. The portions of the plate 49 adjacent the recess 50 are inclined toward said recess 50. As a roll is being mounted in the machine the journal 45 is slid along the inclined portion to thereby be guided into the slot 46 and recess 50, this arrangement facilitating the installation and removal of the spindle. When the journal 45 is held in the horizontal slot 46, the band B evenly and uniformly winds onto spindle 53. However, if for any reason the journal 45 is not retained in the slot 46 but moves over the slot 47, the spindle 53 is wedged and therefore is held against rotation. Thus, the winding of the band is interrupted and this insures that the band will be evenly and uniformly wound. The other end of the spindle 53 is detachably connected to a clutch member 54 journaled in a disc 55 fast to the side frame member 20. A shaft 56 is journaled in the clutch member 54 in a bearing 58 in the housing 59. A clutch member 57 is mounted on shaft 56 in opposition to the clutch member 54. A hand wheel 60 is fast on the shaft 56 exteriorly of the housing 59. Slidably mounted on the shaft 56 intermediate the clutch members 54 and 57 is a weighted shiftable clutch member 61 having a diagonal slot 62 therein and a pin 63 fast in the shaft 56 extends into this slot. When the hand wheel 60 is operated to rotate the shaft 56 in one direction, the action of the pin 63 in the slot 62 moves the shiftable clutch member 61 into engagement with the clutch member 54 whereby the spindle 53 is rotated to wind the band into the roll 44. When the hand wheel 60 is turned to rotate the shaft 56 in the opposite direction, the pin 63 moves through the slot 62 and moves the clutch member 61 from engagement with the clutch member 54 into engagement with the clutch member 57. At the rear end of the machine is a permanently but rotatably mounted take-up spindle T having a shaft 65 connected thereto. The shaft 65 is journaled in bearings in the housing 66 and within the housing 66 a bevel gear 67 is fast on the shaft 65. A shaft 68 is journaled in the housing 66 and fast thereon is a bevel gear 69 which meshes with the bevel gear 67. A shaft 70 is journaled in the housing 59 and extends along the outside of the side frame member 20 in axial alignment with the shaft 68. In the end of the shaft 68 is a socket 71 and a projection 72 on the end of the shaft 70 extends into the socket 71 to provide a flexible connection between the shafts 68 and 70.

and 70. Fast on the shaft 70 within the housing 59 is a bevel gear 73 which meshes with a bevel gear 74 formed on the clutch member 57. Hence, when the shiftable clutch member 61 engages the clutch member 57 and the shaft 56 is rotated, movement is transmitted from the clutch member 57 through bevel gears 74 and 73, shafts 70 and 68, bevel gears 69 and 67 to shaft 65 whereby the take-up spindle T is rotated in a direction such that the gelatin band B stretched over the bed 18 is wound thereupon, suitable means being provided for connecting the end of the gelatin band to the take-up spindle T. To arrange the machine for use, a gelatin band roll is mounted at the front of the machine in the manner described and the end of the band is directed across the bed 18 and connected to the take-up spindle T. The hand wheel 60 is then turned in a direction to cause interengagement of the clutch members 61 and 57 and as the hand wheel 60 is rotated, the gelatin band is withdrawn from the spindle 53 and wound onto the take-up spindle. As the gelatin band is wound onto the take-up spindle, a moistening device to be described operates to moisten the band and to condition it for use and when all the band has been wound from the spindle 53 onto the take-up spindle and past the moistening device so that the gelatinous surface thereof has been thoroughly moistened, it is ready for use. The take-up spindle is permanently mounted in the machine and the distributing roll of the moistening device is likewise permanently mounted. It is therefore possible to align the axes of the spindle and the roll whereby uniform distribution of moisture over the band is insured. If the take-up spindle was loosely mounted in the machine, the axial alignment between this spindle and the periphery of the distributing roll might vary and under such conditions the contact of the band with the distributing roll would not be uniform and an even application of moisture to the band would not result. Therefore, when all of the band has been wound onto the take-up spindle moisture will be uniformly applied thereto and, as stated, it is ready for use. The hand wheel 60 is then turned in the opposite direction whereby the clutch member 61 engages the clutch member 54 and continued rotation of the hand wheel in this direction rotates the spindle 53 and the gelatin band is wound thereon. The gelatin band is wound onto the spindle 53 in a step-by-step manner in the operation of the machine whereby successive portions of the band are arranged over the bed 18 to provide an impression surface. When the band is stretched over the bed to provide an impression surface, it is drawn taut and to this end the following devices are provided. In the disc 55 is a slot 75 which opens into the bore in the disc in which the clutch member 54 is journaled. One end of the slot 75 is wider than the other end and a roller 76 is held in the larger end of the slot 75 by a finger 77 on the rocker 78 pivotally mounted at 79 on the side frame member 20. Pivotally mounted in the side frame member 20 is a rotatable member 80 having an arm 81 thereon normally held in engagement with a stop pin 82 by a spring 83. The end of the rocker 80 opposite the finger portion 77 bears against the lower side of the arm 81 and in this way the roller 76 is held in the larger portion of the slot 75. However, when the arm 81 is moved ninety degrees into engagement with the stop 84 said arm

is disengaged from the rocker 78 and when the clutch member 54 is rotated it acts on the roller 76 and as the rocker 78 is free the finger portion 77 is forced downwardly. When the roller 76 moves into the narrower portion of the slot 75, the clutch member 74 is wedged against rotation and in this way the spindle 53 is held against rotative movement. Fast on the shaft 65 is a disc 85 surrounded by a brake band 86 having spaced lugs 87 and 88 thereon. The disc 85 and brake band 86 are enclosed in a housing 89 having lugs 90 therein. An arm 91 pivotally mounted at 92 extends through an open end in the housing 89 and rests on the lug 87. When the arm 81 on the member 80 is in engagement with the pin 82, there is built light pressure impressed upon the spring 83 which is connected to arm 91. When, however, the arm 81 is turned into the dotted-line position of Fig. 15, the spring 83 is tensioned and this tensioning of the spring so acts on the arm 91 that the end thereof engaging the lug 87 serves to force this lug toward the lug 88 which will be engaging one of the lugs 90 and the movement of the lug 87 toward the lug 88 applies a brake on the shaft 65 whereby the take-up spindle T is secured against rotation. A handle 93 is provided on the member 80 on the outer side of the side frame member 20 and manipulation of this handle secures both spindles against rotation whereby after the band is stretched taut across the bed 18 it is secured in this taut condition. The moistening device previously referred to is shown in Figs. 2 and 6 and consists of a tank 94 mounted at the rear of the machine and in which a pick-up roller 95 is journaled. A bell crank lever 96 is mounted on the shaft 97 which carries the roller 95. On this shaft are arms 98 including bifurcated portions 99 in which trunnions 100 on a roller 101 are mounted. A leaf spring 102 is connected to the shaft 97 and the tank 94 and urges the parts into the position illustrated in Fig. 6. One end of a bar 103 is connected to an arm 104 on the member 105 pivotally mounted in the side frame member 19 and having a handle 106 thereon. In the other end of the bar 103 is a slot 107 through which a pin 108 on one arm of the bell crank lever 96 is extended. A weight 109 is supported by the other arm of the bell crank lever 96 and an arm at the other end of the machine. By turning the handle 106, the bar 103 may be moved to engage the end of the slot 107 with the pin 108 whereupon the bell crank lever 96 is rotated and the roller 101 rolls over the roller 95 into a position whereat it engages the portion of the band wound upon the take-up spindle T. The weight 109 serves to hold the roller in this position. The tank 94 is filled with water and as the band B is wound upon the take-up spindle T, water picked up by the roller 95 is applied to the roll 101 which, in turn, applies the water to the band B as it is wound upon the spindle T. A cock 110 is provided for draining the water from the tank 94.

The carriage arrangement provided is one wherein the platen roller travels on the gelatin band and lifts the wheels on the carriage clear of the trackways and very little load is impressed on the guide rod 25. The chief utility of this guide rod is to afford a center about which the carriage can be pivoted when it is moved from position over the band. It is therefore important that the friction of the guide rod be reduced to a minimum. To this end the guide 70

rod illustrated in Fig. 6 consists of a circular bar on the periphery of which there is a screw thread 111, the face of which is flat to afford sufficient bearing surfaces. The bearings on the carriage 5 and the member 35 are preferably of sufficient length to embrace about three threads of the screw thread 111 to thereby afford sufficient bearing surface. At the same time this screw thread arrangement greatly reduces the contact area of the screw thread and in this way 10 friction is kept at a minimum. In Fig. 10 another arrangement for reducing the friction of the guide rod is illustrated and herein a guide rod 112 is shown which is preferably formed 15 from a square rod twisted so that the corners thereof extend similarly to a screw thread. These corners are flattened as at 113 to provide bearing surfaces. In Fig. 11 a guide rod 114 is illustrated which is turned to form rings 115 thereon with grooves 116 intermediate the rings and in the illustrated arrangement the grooves and rings are of equal size whereby a materially reduced area is provided for contact with the bearings. In Fig. 13 a rod 117 is illustrated 20 which is axially fluted as at 118 to provide four reduced bearing surfaces 119 and the bearings travel on the bearing surfaces 119 which represent but a small portion of the periphery of the bar 117. In Fig. 12, a rod 120 is illustrated 25 which has rings 121 therein similar to the rings 115, and these rings are fluted at 122, these flutes being similar to the flutes 118. This arrangement combines the advantages of the bars 114 and 117 and very restricted bearing portions 30 123 are defined. The bars illustrated in Figs. 6, 10, 11 and 13 all have relieved portions and any foreign matter such as dirt will collect in these relieved portions and in this way wear on the guide rod is reduced for if foreign matter 35 collects on the bearing portions of the rod it is scraped therefrom by the bearings on the carriage to be collected in the relieved portions and in this way the rod is self-cleaning. Additional elimination of friction may be attained by relieving 40 a portion of the bearing surface of the bearings 27 and 28 by providing axial slots 124 (Fig. 6) in these bearings.

In the foregoing description I have described a duplicating machine wherein the gelatin band 45 roll is mounted at the front of the machine. This gelatin band is then wound from the supply to a take-up spindle at the rear of the machine and during this operation the band is conditioned for use by being moistened. After 50 the band has been wound on this take-up spindle, it may then be stretched across the bed of the duplicating machine to be rewound onto the supply roll spindle and it is wound in a step-by-step manner onto this spindle so that 55 successive portions thereof are arranged in position to provide an impression surface. The winding of the band is accomplished by the same handle and an arrangement is provided for connecting either of the rolls to the winding devices 60 so that the band may be wound in either direction. Moreover, a brake arrangement is provided for applying tension on the spindles to hold the band in taut condition in the extent thereof over the bed. The arrangement which permits the 65 gelatin band roll to be mounted at the front of the machine embodies many advantages. It not only eliminates a rewinding of the gelatin band or removal and interchange of the spindles but it also permits facile installation of the spindle. 70 75 It is much easier to mount the spindle at the

front of the machine where everything is accessible than it is to lean over the machine to install a spindle at the rear end thereof. By providing a permanently and rotatably mounted take-up spindle at the rear of the machine and by arranging the spindle at the front of the machine so that it can be removed, the advantages accruing from the manner in which the band is wound are quite marked. The band is first stretched across the bed and then is loosely 10 wound onto the take-up spindle and when it is moistened during this operation the moisture is not squeezed therefrom and furthermore when the band has been used it is rewound back onto the removable spindle which may then be removed from the machine, placed in the rack, and another spindle may be arranged in the machine on which another gelatin band is wound so that operation of the machine may be continued. I have also shown a construction 20 for the guide rod which will materially reduce the friction incident to the reciprocation of the bearings on the carriage therealong and this is manifestly a marked advantage. Furthermore, the guide rod is of the self-cleaning type and 25 therefore wear due to grit and the like collecting on the guide rod is eliminated, since this grit is scraped from the bearing portions on the carriage. The machine also includes an arrangement which insures even and uniform winding of 30 the gelatin band on the removable spindle for when the spindle moves out of proper alignment, which would cause uneven winding, it becomes wedged and cannot be again rotated until it is properly aligned. 35

While I have illustrated and described selected embodiments of my invention, it is to be understood that these are capable of variation and modification and I therefore do not wish to be limited to the precise details set forth but desire to avail myself of such changes and alterations as fall within the purview of the following claims:

I claim:

1. In a duplicating machine, a bed, means for mounting a gelatin band roll at one end of the bed, a take-up spindle at the other end of the bed on which said gelatin band may be wound, and a moistening device associated with said take-up spindle and including a water pan, a roller having a portion of the periphery thereof immersed in water in said pan, supporting means for said roller, means for moving said supporting means to move said roller into engagement with the gelatin band wound on said take-up spindle, and means for maintaining said roller in engagement with the band wound on said take-up spindle as the diameter of the roll of band on said spindle varies. 50

2. In a duplicating machine, a bed, means at 60 one end of said bed adapted to removably receive a spindle, a gelatin band wound on said spindle, a take-up spindle permanently and rotatably mounted at the other end of said bed whereby the gelatin band may be stretched 65 across said bed from said removable spindle and secured to said take-up spindle, means for winding said band to or from said take-up spindle, a moistening device adjacent said take-up spindle and including a water pan, a roller, 70 means supporting said roller whereby a portion of the periphery of said roller may be immersed in water in said pan, means for moving the supporting means for said roller to move said roller into engagement with the band wound on said 75

take-up spindle, and means for maintaining said roller in engagement with the band wound on said take-up spindle as the diameter of the roll of band on said spindle varies.

5 3. In a duplicating machine, a frame, a bed mounted on said frame, a winding device mounted on said frame and including a portion arranged at the front end of said frame, journal means in said frame in alignment with said portion of said winding means whereby one end of a spindle may be releasably connected to one portion of said winding means and the other end thereof may be removably mounted in said journal means, bearings at the rear end of said frame, a take-up spindle journaled in said bearings, and means directly connecting said winding means to said take-up spindle whereby when a gelatin band wound on said first-named spindle is directed across said bed and connected to said take-up spindle the winding means may be operated to wind said band onto or from said take-up spindle.

10 4. In a duplicating machine, a frame, a bed mounted on said frame, a winding device mounted on said frame and including a portion arranged at the front end of said frame, journal means in said frame in alignment with said portion of said winding means whereby one end of a supply spindle may be releasably connected to one portion of said winding means and the other end thereof may be removably mounted in said journal means, bearings at the rear end of said frame, a shaft journaled in said bearings, a take-up spindle fast on said shaft, means directly connecting said winding means to said shaft whereby when a gelatin band wound on said supply spindle is directed across said bed and connected to said take-up spindle the winding means may be operated to wind said band onto or from said take-up spindle, and means for holding said supply spindle and said take-up spindle against rotation whereby the portion of said band stretched across said bed may be held in taut condition to provide an impression surface.

15 5. In a duplicating machine, a frame, a bed mounted on said frame, a winding device mounted on said frame and including a portion arranged at the front end of said frame, said frame having a slot therein at the front end thereof and aligned with said portion of said winding means whereby one end of a spindle may be releasably connected to said portion of said winding means and the other end of said spindle may be journaled in said slot, means for guiding a spindle into said slot and for preventing displacement of the spindle from said slot, a take-up spindle, and means connecting said winding means to said take-up spindle whereby a gelatin band wound on said first-named spindle may be directed across said bed to said take-up spindle to be wound onto or from said take-up spindle upon operation of said winding means.

20 6. In a duplicating machine, a frame, a bed mounted on said frame, a winding device mounted on said frame and including a portion arranged at the front end of said frame, said frame having a slot therein at the front end thereof and aligned with said portion of said winding means whereby one end of a spindle may be releasably connected to said portion of said winding means and the other end of said spindle may be journaled in said slot, means for preventing displacement of the spindle from

said slot, a take-up spindle, means connecting said winding means to said take-up spindle whereby a gelatin band wound on said first-named spindle may be directed across said bed to said take-up spindle to be wound onto or from said take-up spindle upon operation of said winding means, and a moistening device adjacent said take-up spindle and engageable with the band wound thereon to condition said band for use.

25 7. In a duplicating machine, a bed, a take-up roll at the rear end of said bed, and means for releasably mounting the spindle of a gelatin band roll at the front end of said bed and including a slot at one side of the machine adapted to receive a journal on the spindle, and means for guiding the journal into said slot and for releasably holding said journal in said slot.

30 8. In a duplicating machine, means for releasably supporting one end of a spindle, means for removably journaling the other end of said spindle, a member cooperating with the periphery of said spindle to position the same in said journaling means, and means for guiding the journal into said slot and for preventing displacement of said spindle from said journaling means.

35 9. In a duplicating machine, a bed, a take-up spindle permanently and rotatably mounted at the rear end of said bed, and means for releasably mounting the spindle of a gelatin band roll at the front end of said bed and including portions in which said spindle will wedge when said spindle is not aligned with said take-up spindle to cause the gelatin band to evenly and uniformly wind on the releasably mounted spindle.

40 10. In a duplicating machine, a bed, a take-up roll at the rear end of said bed, means for releasably mounting the spindle of a gelatin band roll at the front end of said bed and including a slot at one side of the machine and including a horizontally extending portion terminating in a vertically extending portion whereby a journal on the spindle may be arranged in the horizontally extending portion of said slot to be mounted in the machine so that the gelatin band will uniformly and evenly wind thereupon, and means for releasably retaining the journal on said spindle in the horizontally extending portion of said slot, the journal on said spindle being adapted to move into the vertically extending portion of said slot to wedge therein to prevent winding of the band thereupon whereby the band will be prevented from being wound on the spindle other than in a uniform and even manner.

45 11. In a duplicating machine which has a bed, a take-up roll at the rear end of the bed, means for releasably mounting the spindle of a gelatin band roll at the front of the bed whereby a gelatin band may be withdrawn from said spindle and directed across said bed to said take-up roll so that the portion thereof stretched across said bed provides an impression surface, the combination of a carriage reciprocal over said bed and adapted to apply sheets to said impression surface applied to said band to take impressions therefrom, a cradle, a guide rod mounted in said cradle, yieldable means for maintaining said guide rod in guiding position, bearings on said carriage and adapted to move along said guide rod to insure uniform movement of the carriage over said bed upon repeti-

tious operations thereof, said guide rod having relieved portions providing restricted bearing surfaces whereby the friction between the bearings on said carriage and said guide rod is reduced.

12. In a duplicating machine, a bed having a gelatin band stretched thereover to provide an impression surface, a carriage reciprocal over said bed and adapted to apply sheets to said impression surface to take impressions therefrom, a guide rod in said machine, bearings on said carriage adapted to slide along said guide rod to insure uniform reciprocation of said carriage over said impression surface upon repetitious operations thereof, said guide rod having relieved portions in the periphery thereof whereby restricted bearing surfaces are provided thereon so that the surface contact between said bearings and said bearing surfaces is reduced to thereby reduce the friction incident to movement of said bearings along said guide rod, and means for supporting said guide rod for floating movement to further reduce friction incidental to the reciprocation of the bearings on the carriage therealong.

13. In a duplicating machine, a bed having a gelatin band stretched thereover to provide an impression surface, a carriage reciprocal over said bed and adapted to apply sheets to said impression surface to take impressions therefrom, a guide rod in said machine, bearings on said carriage adapted to slide along said guide rod to insure uniform reciprocation of said carriage over said impression surface upon repetitious operations thereof, said guide rod having a screw thread on the periphery thereof flattened to provide bearing surfaces whereby the surface contact between said bearings and said guide rod is reduced to thereby reduce the friction incident to the reciprocation of said bearings along said guide rod to a minimum, and means for supporting said guide rod for floating movement to further reduce friction incidental to the reciprocation of the bearings on the carriage therealong.

14. In a duplicating machine, a bed having a gelatin band stretched thereover to provide an impression surface, a carriage reciprocal over said bed and adapted to apply sheets to said impression surface to take impressions therefrom, a guide rod in said machine, and bearings on said carriage adapted to slide along said guide rod to insure uniform reciprocation of said carriage over said impression surface upon repetitious operations thereof, said guide rod having alternate rings and grooves of substantially equal size formed in the periphery thereof to reduce the peripheral area of said guide rod to reduce the contact between said bearings and said guide rod whereby the friction incident to the reciprocation of said carriage along said guide rod is reduced.

15. In a duplicating machine, a bed having a gelatin band stretched thereover to provide an impression surface, a carriage reciprocal over said bed and adapted to apply sheets to said impression surface to take impressions therefrom, a guide rod in said machine, bearings on said carriage adapted to slide along said guide rod to insure uniform reciprocation of said carriage over said impression surface upon repetitious operations thereof, said guide rod having axially extending flutes therein providing restricted bearing surfaces at spaced points on said guide rod, the bearings on said carriage contacting

with said restricted bearing surfaces so that the friction incident to the reciprocation of said bearings along said guide rod is reduced, and means for supporting said guide rod for floating movement to further reduce friction incidental to reciprocation of the bearings on the carriage therealong.

16. In a duplicating machine, a bed having a gelatin band stretched thereover to provide an impression surface, a carriage reciprocal over said bed and adapted to apply sheets to said impression surface to take impressions therefrom, a guide rod in said machine, and bearings on said carriage adapted to slide along said guide rod to insure uniform reciprocation of said carriage over said impression surface upon repetitious operations thereof, said guide rod having alternate rings and grooves of substantially equal size therein and having axially extending flutes extending through said rings whereby materially reduced bearing surfaces are formed on the periphery of said rod, the bearings on said carriage engaging said restricted bearing surfaces to thereby reduce the friction incident to the reciprocation of said bearings along said guide rod.

17. In a duplicating machine, a bed having a gelatin band stretched thereover to provide an impression surface, a carriage reciprocal over said bed and adapted to apply sheets to said impression surface to take impressions therefrom, a guide rod in said machine, bearings on said carriage adapted to slide along said guide rod to insure uniform reciprocation of said carriage over said impression surface upon repetitious operations thereof, said guide rod having reduced portions in the periphery to reduce the peripheral area thereof, and said bearings having relieved portions therein to reduce the area thereof contacting with the periphery of said guide rod whereby friction incident to the reciprocation of said bearings along said guide rod is reduced.

18. In a duplicating machine which has a moistening device including a roller engageable with the gelatinous band of the duplicating machine during the winding of the band, a bed, a drum permanently and rotatably mounted in said machine at the rear end of said bed and in parallel relation with the roller of the moistening device, said drum having connecting means on the periphery thereof and providing a take-up spindle, and means at the front end of said bed to removably support a spindle having a gelatin band wound thereon for rotatable movement and including means for guiding the spindle into a winding position whereby a gelatin band wound on said spindle may be withdrawn from the spindle and stretched across said bed and attached to the connecting means on said drum whereby the band may be moistened by said roller as it is wound on the drum.

19. In a duplicating machine which has a moistening device including a roller engageable with the gelatinous band of the duplicating machine during the winding of the band, a frame including side members, a bed mounted on said frame, bearings in said side members adjacent the rear end of said frame, a take-up spindle having journals thereon permanently and rotatably mounted in said bearings to support said take-up spindle in parallel relation with the roller of the moistening device, means in said side members for removably supporting a gelatin band spindle at the front end of said frame whereby a spindle having a gelatin band wound

thereon may be removably mounted at the front end of said frame and the band may be withdrawn therefrom and directed across said bed, means on said take-up spindle for detachably connecting said band to said take-up spindle to facilitate winding of said band on said take-up

spindle, and means including an operating device spaced from said take-up spindle for rotating said take-up spindle to wind said band thereon whereby the band may be moistened by said roller as it is wound on said take-up spindle. 5

JOHN J. FLANIGAN.
